CARRYING CASE FOR PHOTOGRAPHIC CAMERA
AND ACCESSORIES OR SIMILAR ARTICLE

James M. Conner, Glendale, and Henry Dreyfuss, South
Pasadena, Calif., assignors to Polaroid Corporation,
Cambridge, Mass., a corporation of Delaware

Filed Sept. 3, 1965, Ser. No. 86,832

Term of patent 14 years

(Cl. D87—5)

FIG. 1

FIG. 2

FIG. 3

FIG. 4

FIG. 2 is a front elevational view thereof in open condition;

FIG. 3 is a side elevational view thereof in closed condition;

FIG. 4 is a rear elevational view thereof; and

FIG. 5 is a bottom plan view thereof.

Conventional carrying straps are represented fragmentarily for illustrative purposes only.

The dominant features of the design reside in the bowed front of the case and the concave curvature of the front flap on either side of the clip, as shown.

We claim:

The ornamental design for a carrying case for photographic camera and accessories or similar article, substantially as shown and described.
